UNITED STATES PATENT OFFICE.

PHILIP THEODORE ROBIN, OF ASPINWALL, AND WILLIAM MAYO VENABLE, OF PITTSBURGH, PENNSYLVANIA, ASSIGNORS TO BLAW-KNOX COMPANY, A CORPORATION OF NEW JERSEY.

LEVER-ARM BUCKET.

Application filed June 6, 1927. Serial No. 198,644.

This invention relates to improvements in lever arm buckets and more particularly to the construction of lever, hinges and corner brackets and their relative arrangements in 5 buckets of this type.

Heretofore in the construction of lever arm buckets it has been the practice to cast the housing for the lever arm sheaves integral with the drum in which the main hinge pin is 10 received, and either to extend this casting so as to connect it directly to one of the scoops, or to secure the drum rigidly to one of the scoops by forming it integrally with one pair of hinges.

15 It is among the objects of this invention to secure those structural advantages which result from a construction of lever arm bucket wherein the lever arm is integral with the drum and rigidly secured both to the back 20 of the scoop and to one pair of the hinges without, at the same time, making a casting which is as large as is ordinarily contemplated, and, consequently, as expensive as would be necessary if all these parts were 25 cast in a single piece.

A further object of this invention is to 30 provide a construction of lever arm bucket comprising several component parts arranged to be assembled in final relation in such manner as to provide a bucket which is as strong or stronger than if these several parts were 35 formed in one piece.

With these objects in view, that part of the bucket which is usually termed the lever 40 arm is constructed of several parts herein-after designated as the drum, the lever arm plates, the sheave housing and one pair of hinges. Preferably the drum, hinges and sheave housing are in the form of steel castings, while the lever arm plates together with any stiffening or reinforcing members which may be used in connection therewith are formed of rolled steel. The drum and the sheave housing are rigidly connected together 45 in the manner to be hereinafter described, and the pair of hinges are fitted upon the drum in such manner that, while normally not movable with respect to the drum, they are still capable of slight rotation 50 about the axis of the drum should, during the operation, the bucket be subjected to unequal strains. By this arrangement the tendency

for the hinge castings to break, this being considerable when the drum and hinges are cast integrally, is greatly reduced.

It is well known that it is possible to procure rolled steel sections, including plate, which is capable of being subjected to much greater strains and much less likely to contain imperfections than the ordinary grades of cast steel of good quality. Consequently, where such rolled sections can be used, it is 55 decidedly advantageous to employ them in place of the usual castings. This invention 60 contemplates, therefore, the provision and construction of a lever arm which is free from the disadvantages and objectionable features resulting in such arms constructed according to other methods at the same time that 65 these lever arms may be manufactured conveniently and economically.

Other objects, and objects relating to details of economy and construction, will appear more fully hereinafter.

The invention consists substantially in the 75 construction, combination, location and relative arrangements of parts, all as will be more fully hereinafter set forth, as shown in the accompanying drawings, and finally 80 pointed out in the appended claims.

In the drawings:

Figure 1 is a side elevation of a lever arm bucket embodying the principles of this invention; and

Figure 2 is a front elevation, partly in section; corresponding to the construction shown in Figure 1.

Referring more particularly to the drawings, it will be seen that the bucket comprises a pair of scoops 10-10' swingably mounted 90 at their outer corners 11 to the corner bars 12, in this case four in number. These bars 12 are of usual construction, and are pivoted together in pairs upon a head, designated generally by the reference numeral 13.

The lever arm of the bucket includes a pair of laterally spaced plates 15-15', the bottom ends of which are rigidly secured, preferably by bolting or riveting, to one of the scoops 10'. The upper ends of these plates 15-15' 100 are secured one on either side of the lever arm sheave housing 16 by bolts 17, and openings 18 are provided in the plates through which may be inserted the cap members 19.

for the sheave bearing 20. The sheave housing 16 including the sheave 21 and its bearing 20 may be mounted as a unit between the upper ends of the plates 15-15.

5 These plates 15-15 are further provided with enlarged central openings 22 so as to permit their being slipped over the opposite ends of the main drum or cylinder casting 23. This latter casting, which is of hollow form, 10 is formed with a pair of spaced annular flanges 24. Arranged in parallel relation to the outer faces of these flanges are secured the plates 15 by means of bolts or rivets 25. Preferably the drum 23 is provided with finished bosses 37 arranged to fit snugly within the central openings 22 of the plates so that substantially all of the strain which is transmitted from the lever arm plates to the drum is taken by these bosses without imposing any 20 strain upon the securing bolts or rivets 25.

The opposite ends of the drum 23 terminate in finished hubs 26 within which is rotatably mounted the main hinge pin 27. It is preferable to provide a bushing 28 between the internal bearing surfaces of the hubs and the main hinge pin. As most clearly appears in Figure 2 it will be seen that the hubs 26 of the drum terminate short of the ends of the main hinge pin and that each of these hubs 30 at the inner end thereof is provided with an annular flange 29. Mounted upon each of these hubs 26 with the inner end thereof abutting the annular flange 29 is the inner hinge collar 30. It is to be noted that the outer 35 end of the collar 30 terminates in the plane of the outer end of the finished hub 26.

The outer hinge collars 32 fit snugly over the projecting ends of the main hinge pin 27 and are fixed against rotation with respect thereto by the provision of dowel pins 33 passing through the collars 32 and the hinge pin 27. In the construction just described it will be seen that the inner and outer hinge collars 30 and 32 are relatively rotatable, the shaft 45 27 turning in the hub bushings 28. It will further be seen that only one joint subject to end thrusts is provided at either side of the lever arm through which sand or grit can possibly work its way between the bearing 50 surfaces of the inner hinges. In order to properly provide for lubrication between these bearing surfaces a grease plug 34 may be employed whenever it is deemed desirable to use grease for lubricating purposes. If desired, 55 the hollow space or chamber 35 which is provided between the hub casting 23 and the main hinge pin 27 may be filled with lubricant.

Instead of employing separate hinge members and corner brackets for the bucket, the hinge collars 30 and 32 are formed integrally with the depending corner brackets 36 so as to obviate the necessity for separately riveting or bolting the hinge and corner bracket castings to the scoops 10-10'. Not only do these

combined hinge and corner bracket castings afford maximum strength in these parts, but they also make it practicable to conduct the machine work more economically at the same time that they avoid the possibility of errors which may occur when these parts are separately riveted or otherwise secured to the scoops.

An important feature from the standpoint of manufacture is the facility with which the several component parts of the bucket may be finished and assembled in final relation. The lever arm drum 23, being in the form of a single casting can be readily finished in the lathe, thus considerably decreasing the cost of production. The lever arm plates 15 are formed with their central openings of a diameter sufficient to permit their being readily slipped over the end hubs 26 after the drum is entirely finished, it being further observed that the hinges 30 can be slipped over these hubs afterwards. Still further, the housing 16, regardless of whether it be for one or more sheaves, may be mounted in position between the plates 15 with facility and whenever desired.

What is claimed as new and useful is:—

1. In a bucket, the combination of a lever arm hub, a pair of independently formed plates secured thereto in spaced relation and constituting the arm proper, and a sheave housing secured between the plates.

2. In a bucket the combination of a pair of scoop members, a hinge pin, a lever arm hub mounted on the pin, and a pair of independently formed plates secured thereto in spaced relation and constituting the arm proper, said plates being secured at their lower ends to a scoop member.

3. In a bucket the combination of a pair of scoop members, a hinge pin, a lever arm hub mounted on the pin, a pair of independently formed plates secured thereto in spaced relation and constituting the arm proper, said plates being secured at their lower ends to a scoop member, and a sheave housing secured between the plates.

4. In a bucket the combination of a pair of scoop members, a hinge pin, a lever arm hub mounted on the pin, a pair of independently formed plates secured thereto in spaced relation and constituting the arm proper, said plates being secured at their lower ends to a scoop member, a sheave housing secured between the upper ends of said plates, and a pair of independently formed scoop hinge members mounted on the hub.

5. In a bucket, the combination of a pair of scoop members, a hinge pin, a lever arm hub mounted on the pin, and a pair of independently formed scoop hinge members mounted on the hub.

6. In a lever arm bucket apparatus, a drum casting for a main hinge pin, and a lever arm for effecting relative rotation between said.

pin and casting, said arm comprising a pair of plate members secured to said casting intermediate the ends thereof.

7. In a lever arm bucket apparatus, a lever arm drum casting terminating at its opposite ends in bearing hubs, a hinge pin axially disposed within said casting with the opposite ends thereof projecting beyond the outer edges of said hubs, and a pair of combined hinge and corner bracket castings at opposite sides of the apparatus one casting of each pair being slipped over said bearing hubs and the other being keyed to the projecting ends of said hinge pin.

15 8. A lever arm bucket apparatus including a transversely extending main hinge pin, a lever arm drum surrounding said pin and a pair of inner and outer hinge members located at opposite ends of said pin and drum, said inner hinge members being slipped over said end portions of the drum and said outer hinge members being keyed to said pin.

9. A lever arm bucket apparatus, in combination, a transversely extending hollow casting provided with integrally formed annular flanges intermediate its ends, a hinge pin axially disposed within said casting, a pair of scoops respectively supported by said casting and said hinge pin, a pair of plates secured one to each of said flanges, said plates extending in opposite directions from said flanges, and a sheave housing secured between said plates to one side of said casting.

10. A lever arm bucket apparatus, in combination, a transversely extending drum cast-

ing, a pair of annular flanges on said casting intermediate the opposite ends thereof, said casting being provided with a longitudinally extending bore, a hinge pin axially disposed within said bore, the diameter of said pin being less than the diameter of the major extent of said bore, a pair of scoops respectively secured to said drum casting and to said hinge pin, a plate secured to each of said flanges, said plates extending in substantially opposite directions from said casting, and a sheave housing mounted between the portions of said plates lying to one side of said casting, the opposite ends of said plates being secured to one of said scoops.

11. A lever arm bucket apparatus including a transversely extending hollow member, said member terminating at the opposite ends thereof in bearing hubs, a pair of spaced annular flanges on said member intermediate said hubs, a main hinge pin extending through the longitudinal bore of said hollow member with the opposite ends thereof supported in said bearing hubs, and a pair of plates extending substantially at right angles to said member, each of said plates being secured to one of said annular flanges whereby to provide a lever arm for effecting relative movement between said member and said hinge pin.

In testimony whereof, we have hereunto signed our names.

PHILIP THEODORE ROBIN.
WILLIAM MAYO VENABLE.
